UNITED STATES PATENT OFFICE.

ROBERT TRENTZSCH, OF LEIPZIG, GERMANY, ASSIGNOR TO THE FIRM OF ELEKTROGRAVÜRE GESELLSCHAFT MIT BESCHRÄNKTER HAFTUNG, OF LEIPZIG, GERMANY.

ENGRAVING-MACHINE.

SPECIFICATION forming part of Letters Patent No. 732,472, dated June 30, 1903.

Application filed March 6, 1903. Serial No. 146,434. (No model.)

To all whom it may concern:

Be it known that I, ROBERT TRENTZSCH, a subject of the King of Saxony, and a resident of Leipzig-Neustadt, Saxony, Germany, have ⁵ invented certain new and useful Improvements in Engraving-Machines, of which the following is a specification.

This invention relates to a machine for engraving reliefs which is so constructed that ¹⁰ friction is avoided, sunk and raised models may be copied, and an accurate reproduction of the model is obtained.

In the accompanying drawings, Figure 1 is ¹⁵ a plan of an engraving-machine embodying my invention, and Fig. 2 a front elevation of the same with some of the parts omitted.

The letter *k* represents the bed-plate of the machine, to which is connected by upright pivot *a* a bearing *a'*, having a forwardly-extending pivot *b*. This pivot is embraced by the hub *c'* of a lever *c*, so that a universal joint is formed between the bed-plate and lever. Upon one arm of lever *c* are mounted a pair of tracers *e e'*, which extend in opposite directions. If the machine is in use, only one of these tracers—viz., either tracer *e* or tracer *e'*—is in operation, the selection of the one to be used depending upon the nature of the model and of the copy desired. If, for ³⁰ instance, a raised copy is to be made from a raised model *i'*, the latter is attached to a disk *A'* opposite tracer *e'*, so that tracer *e'* is in operation. If, however, a raised copy is to be made from a sunk model *i*, the latter is ³⁵ attached to a disk *A* opposite tracer *e*, which is now put in operation. It will be seen that by this arrangement it is possible to make raised copies from raised models or raised copies from sunk models, and vice versa. The ⁴⁰ disks *A A'* of patterns *i i'* are secured to mandrels *i² i³*, respectively, which turn in bearings *h h'*. They receive rotary motion by worm-wheels *m¹* or *m²* in the manner herein-after described. The engraving-tool *d*, ⁴⁵ rotated by electric or other power, is adjustably mounted upon the other arm of lever *c* and engages the work-piece *g*, which is mounted upon a disk *B*, attached to a mandrel *f*, that turns in suitable bearings of a slide-rest ⁵⁰ *f*. This slide-rest is provided with set-screws

f², entering a longitudinal groove *k'* of bed-plate *k*, so that the slide-rest is adjustable upon the bed-plate. Thus by setting the engraving-tool *d* and slide-rest *f* to the right or left the size of the copy produced can be increased or diminished. The mandrel *f'* carries a worm-wheel *m*, by means of which it is rotated.

The lever *c* is held against the model *i* or *i'*, which is either attached to disk *A* or to disk *A'* ⁶⁰ by springs *l l'*, and is moved in the usual manner by a screw and nut or otherwise, so that the tracer is projected radially across the model. As the tracer is conducted from the center toward the periphery of the model it ⁶⁵ describes a small arc, of which the fulcrum of lever *c* is the center, a similar arc being simultaneously described by the engraving-tool upon the work-piece. The model and work-piece rotate in opposite directions, as ⁷⁰ indicated by the arrows in Fig. 2. The tracer *e* therefore arrives at a given point of the model earlier than the engraving-tool arrives at a corresponding point of the work-piece within the same parallel circle. If the engraving is ⁷⁵ to be a true copy of the model, it is necessary that all points of the model describe the same length of way before being reached by the tracer, as the corresponding points of the work-piece must describe before being ⁸⁰ reached by the engraving-tool. If the model and the work-piece are of different size, the length of way described must be in like manner of proportionate size. To illustrate: The point *z'* of the model would simultaneously describe a complete circle *D* minus the arc *z' l'*, while the point *z* of the work-piece would describe the circle *E* plus the arc *z d*. To avoid this defect, which would produce a distortion in the engraving, I so regulate the ⁸⁵ speed of the model and work-piece that the ways described for each given point thereon are equal when the model and work-piece are of the same size and that the ways are proportionate when model and work-piece are of different size. The means for carrying out this result are as follows: The lever *c* carries at its right end an arm *c²*, passing through a perforated sleeve *o'*. This sleeve carries a pin *o*, which is adapted to slide within a sleeve ⁹⁰ *o*.

o⁷ of a slide *o²*, guided in suitable manner within the frame of the machine. A tapped perforation of slide *o²* is engaged by a screw-shaft *o*, that receives motion from counter-shaft *r* 5 by stepped pulley *r²*, belt *r³*, stepped pulley *o³*, worm *o⁴*, and worm-wheel *o⁵*, fast on shaft *o*. The shaft *o* rotates by bevel-gear *u u'*, the shaft *r'* of a worm *s'*. This worm engages a worm-wheel *t'*, fast on shaft *w'*, which carries 10 also two eccentrics *y'*. Against each eccentric is held by spring *l²* a roller *x*, hung in the lower arm of a lever *q*, fulcrumed at *w*. The upper arm of each lever *q* is by link *q'* connected to a sliding bearing *y*, through which 15 passes the hub of a tubular worm *s*, which is taken along by the bearing by means of collars *s²*. One worm *s* engages worm-wheel *m'* of mandrel *i²* and is slidably upon one end of counter-shaft *r*, while the other worm *s* engages worm-wheel *m²* of mandrel *i³* and is 20 slidably upon a shaft *r⁴*. Both worms participate in the rotation of their respective shafts by feather-and-groove connections. Counter-shaft *r* receives motion from power-pulley 25 *r⁵* by gear-wheels *r⁶ r⁷*, while shaft *r⁴* receives motion from gear-wheel *r⁷* by gear-wheel *r⁸*, shaft *r⁹*, and gear-wheels *r¹⁰ q¹¹*. The opposite end of shaft *r* is provided with a worm *s³*, which is fixed thereon and engages the worm-wheel *m* of mandrel *f'*. By the mechanism 30 described the oscillation of lever *c* will be accompanied by a simultaneous rotation and advance of the worm *s*, which will retard the rotation of the model in relation to the rota-

tion of the work-piece in such a manner that 35 corresponding points of the model and work-piece will describe the same or proportionate ways.

What I claim is—

1. In an engraving-machine, the combination of a lever with a pair of tracers projecting therefrom in opposite directions, and with a pair of model-carrying mandrels arranged opposite said tracers, substantially as specified. 45

2. In an engraving-machine, the combination of a lever with a tracing-tool and an engraving-tool connected thereto, means for tilting the lever, mandrels for carrying the model and work-piece respectively, and means for simultaneously rotating said mandrels in opposite directions at different speeds, substantially as specified. 50

3. In an engraving-machine, the combination of a lever with a tracing-tool and an engraving-tool connected thereto, a shaft for tilting the lever, a sliding rotatable worm operatively connected to the shaft, a model-carrying mandrel, and a worm-wheel on said mandrel which is engaged by the worm, substantially as specified. 55

Signed by me at Leipzig, Germany, this 18th day of February, 1903.

ROBERT TRENTZSCH.
